CHARLES T. MEYER, OF BERGEN, NEW JERSEY, ASSIGNOR TO EDWARD C. SAMPSON, OF NEW YORK, N. Y.

Design No. 2,579, dated February 12, 1867.

DESIGN FOR FLOOR OIL-CLOTH.

The Schedule referred to in these Letters Patent and making part of the same.

TO ALL WHOM IT MAY CONCERN:

Be it known that I, CHARLES T. MEYER, of the town of Bergen, Hudson county, State of New Jersey, have originated and designed a new Pattern for Floor Oil-Cloths, Carpets, or other fabrics, of which the following is a full, clear, and exact description, reference being had to the accompanying specimens or drawings, making part of this specification, marked and designated as Marble No. 6, which fully represents said design, and is sufficient, without further aid, to enable any person skilled in the art to repeat it for practical use. The colors employed for the different portions of this design may be varied to suit the taste or views of the manufacturer.

What I claim as my invention, and desire to secure by Letters Patent, is—

The design or pattern for floor oil-cloths, carpets, or other fabrics, herein shown and set forth.
